UNITED STATES PATENT OFFICE.

JOHN FROELICH, OF ST. PAUL, MINNESOTA.

INTERNAL-COMBUSTION ENGINE.

1,332,211.

Specification of Letters Patent.

Patented Mar. 2, 1920.

Application filed October 25, 1917, Serial No. 198,403.

To all whom it may concern:

Be it known that I, JOHN FROELICH, a citizen of the United States, residing at St. Paul, in the county of Ramsey and State 5 of Minnesota, have invented new and useful Improvements in Internal-Combustion Engines, of which the following is a specification.

My invention relates to improvements in 10 internal combustion engines, and is a simplified form of the two-cycle internal combustion engine in which the cylinders are arranged in pairs and coöperate with each 15 other in the introduction of fuel, as heretofore described in my application for patent filed December 3, 1915, and bearing Serial No. 64,890.

The general objects of the invention are 20 to provide a simple and efficient engine of the piston-valve type having means for thoroughly scavenging the cylinders after each explosion and for introducing charges of fuel of uniform quantity and composition into the cylinders, and also to produce 25 an operating cycle in which the scavenging and introduction of charges of fuel shall be so related as to result in increased efficiency.

A further object is to simplify the construction embodied in my application Serial Number 64,890, and eliminate the possibility of escape through the exhaust ports of unburned gases prior to the covering of such ports by the piston.

Other novel features of construction will 35 be hereinafter described and pointed out in the claims.

In the accompanying drawings, Figure 1 is a longitudinal sectional view of my engine; Fig. 2 is a central transverse sectional view taken through one of the engine cylinders and illustrates the piston-valve arrangement and the various ports and passageways; Fig. 3 is a vertical section 45 taken on the line 3—3 of Fig. 2; Fig. 4 is a section on the line 4—4 of Fig. 2; Fig. 5 is a section on the line 5—5 of Fig. 2; and Figs. 6, 7, and 8 are diagrammatic views, each showing the cylinders of the engine 50 with the moving parts in different relative positions.

Referring to the drawings, I have used the reference letters A and B to indicate the differential cylinders. These cylinders 55 are identical and are mounted side by side upon a crankcase C having therein a re-

movable dividing wall C' formed of separable sections adapted to divide said crankcase into compartments, one for each cylinder. A crankshaft 1 revoluble in the crankcase C is formed with a crank 2 in each compartment, said cranks being arranged at 180° with respect to each other. Differential pistons A' and B' within the cylinders A and B respectively are connected by pit- 60 men 3 to said cranks 2, and move in opposite directions.

The differential cylinders A and B comprise respectively explosion chambers 4^a, 4^b and pump chambers 5^a, 5^b, said pump chambers being enlargements of the explosion chambers and located in axial alinement therewith. The explosion chambers 4^a, 4^b are respectively furnished with air inlet ports 6^a, 6^b and with exhaust ports 7^a, 7^b. 70 Gas admission ports 8^a, 8^b also communicate with said explosion chambers and are situated directly above the air inlet ports 6^a, 6^b. Spark plugs (not shown) are placed in the upper ends of the explosion chambers 80 for igniting the gas in said cylinders. Said pump chambers 5^a, 5^b are respectively provided at the upper ends with a common inlet and outlet port 9^a, 9^b, which permits the passage of gas into and out of said 85 chambers. The compartments or air compression chambers 10^a, 10^b in the crankcase C are provided with channels 11^a, 11^b, communicating respectively with the air inlet ports 6^a, 6^b in the explosion chambers. A 90 puppet-valve 12 for each compartment 10^a, 10^b is placed at one side of the crankcase and admits air to its said compartment. The differential pistons A', B' comprises 95 respectively working pistons a and b and pump pistons a' and b', the former fitting the explosion chambers 4^a, 4^b, and the latter the pump chambers 5^a, 5^b. The working pistons a and b compress gas within the explosion chambers 4^a, 4^b and receive im- 100 pulses upon the ignition of the gas, while the pump pistons a' and b' serve a double purpose, namely: to draw gas into the pump chambers 5^a, 5^b and expel the same therefrom and also to draw air into the air 105 compression chambers 10^a, 10^b and compress said air therein. Deflectors 37 are placed upon the top of said pistons A', B' and force air and gas (both introduced under pressure against the top of the explosion chambers 4^a, 4^b).

A housing D, containing two oppositely

working piston-valves E and F and a shaft 13, having oppositely arranged cranks 14, is arranged on the admission side of the cylinders A and B. Pitmen 15 connect said piston-valves E and F to the cranks 14 on said shaft and said shaft is journaled in the housing D and revolved at the same rate of speed as the main crankshaft 1 by means of a train of gears 16 driven by said main 10 crankshaft. A casing 17 incloses said gears, and together with the housing D, completely incloses the valve mechanism of my engine.

Within the upper end of the housing D 15 are situated two valve cylinders 18^a and 18^b, each having a machined valve-liner 20 rigidly secured therein, within which the piston-valves E and F respectively travel. Said valve-liners 20 prevent leakage around 20 said valves and facilitate the accurate positioning of the valve ports hereinafter described.

A horizontal partition 21 in the upper end of the housing D forms a storage or 25 transfer chamber G, within which the upper ends of the valve cylinders 18^a, 18^b project. Apertures 22 are formed in the projecting ends of said valve cylinders and two additional ports 23^a, 23^b are formed in said valve 30 cylinders 18^a, 18^b respectively at the bottom of said transfer chamber G; said ports 23^a, 23^b and apertures 22 respectively permitting the admission and exit of gas to and from said transfer chamber. Below said ports 35 23^a, 23^b in the valve-cylinders 18^a, 18^b are located channels 25^a, 25^b which communicate with the exterior of the housing D and said valve cylinders 18^a, 18^b respectively, and provide a passageway for gas from a 40 carbureter (not shown) to the piston-valves E and F. Ports 27^a, 29^a, and 27^b, 29^b are formed in the opposite sides of said valve cylinders 18^a, 18^b respectively, and channels 31^a, 31^b respectively provide means of 45 communication between said ports 27^a, 27^b and the gas admission ports 8^a, 8^b; while channels 33^a, 33^b perform a similar function between the ports 29^a, 29^b and pump chamber ports 9^a, 9^b. Each piston-valve E and F 50 has two converging passageways 35^a, 36^a and 35^b, 36^b respectively extending diametrically therethrough; the direction of convergence being toward the engine cylinders, and said passageways 35^a, 35^b are so positioned 55 that during substantially one-third of a revolution of the shaft 13 (and likewise of the main crank shaft 1), said passageways 35^a, 35^b register with the ports 23^a, 29^a and 23^b, 29^b respectively; while during substantially 60 the opposite one-third revolution of said shaft the passageways 36^a, 36^b register with the channels 25^a, 25^b and ports 29^a, 29^b.

The operation of my engine will now be 65 described, taking as a convenient starting

point in the operating cycle the explosion of a charge in one of the cylinders. Beginning with an explosion in the cylinder A (Fig. 6), the differential piston A' moves downward upon its forward stroke, the piston a' compressing air in the compression chamber 10^a, the puppet-valve 12 now being closed, and the air inlet port 6^a in the cylinder being covered by the piston a. The suction thus caused in the pump chamber 5^a by the 70 downwardly moving piston a' draws gas from a carbureter (not shown) communicating with the channels 25^a, 25^b through said channel 25^a, thence through the passageway 36^a in the piston-valve E, and 80 through the port 29^a in the valve cylinder 18^a, and thereafter through the passageway 33^a and into the pump chamber 5^a. The differential piston B' is carried upward 85 during such downward stroke of the differential piston A' and its piston b' draws a supply of air through the puppet-valve 12 into the compression chamber 10^b and compresses the gas for a short interval in the pump chamber 5^b, then forces said gas 90 through the port 9^b and channel 33^b into the transfer chamber G through the passageway 35^b in the piston-valve F, which now registers with the ports 29^b and 23^b in the valve cylinder 18^b. 95

Just before the piston A' reaches the end of its forward stroke (Fig. 7), the gas admission port 8^a, air inlet port 6^a, and exhaust port 7^a of the explosion chamber 4^a, are uncovered by said piston. The uncovering of the exhaust port 7^a releases the burnt gases and the opening of the air inlet port 6^a permits the inflow of scavenging air from the air compression chamber 10^a through the channel 11^a. This inflowing current of 100 air strikes the baffle-plate or deflector 37 on the top of the piston a and is first deflected upward to reach and drive out all of the burnt gases through the exhaust port 7^a. No gas is admitted to the explosion chamber at this point, the piston-valve E blocking the channel 31^a communicating with the gas admission port 8^a. The companion piston B' at this time is completing the compression of the gas in the explosion chamber 4^b, also completing the expulsion of the 110 gas from the pump chamber 5^b, and further completing the intake of air to the compression chamber 10^b. 115

At the beginning of the return stroke of 120 the piston A' in said cylinder A (Fig. 8), and after the air inlet port 6^a is covered by the piston a (but before the exhaust port 7^a is completely covered), the piston-valve E uncovers the port 27^a in the valve cylinder 18^a and a charge of gas from the transfer chamber G first passes through the apertures 22 in the top of said valve cylinder 18^a and then rushes through the gas admission port 8^a into the explosion chamber 4^a. The 130

influx of said gas displaces the scavenging air, as said scavenging air had displaced the burnt gas, thus resulting in supplying the explosion chamber with a complete charge 5 of fresh gas upon the initial return movement of the piston A'. Continued upward movement of said piston A' operates to compress the gas within the explosion chamber 4^a, force the gas from the pump chamber 5^a 10 through the passageway 35^a of the piston-valve E, and into the transfer chamber G via the port 23^a, and also draw air through the puppet-valve 12 into the compression chamber 10^a. This completes one turn of 15 the crank-shaft and said operation is repeated upon each revolution thereof.

Having described my invention, what I claim as new and desire to protect by Letters Patent is:

20 1. In an internal combustion engine, a pair of differential cylinders, each comprising a pump chamber and an explosion chamber, said pump chambers each having a common inlet and outlet port and said explosion chambers each having a gas admission port, an air admission port and an exhaust port, a crankcase divided into air compression compartments, one for each cylinder, channels connecting said air compression compartments of each cylinder with the air admission port in the same cylinder, a differential piston for each of said cylinders, comprising a power piston arranged to uncover said gas admission port, air admission port 25 and exhaust port at the end of its power stroke, and a pump piston adapted to draw gas into the pump chamber and expel the same therefrom and also draw air into the crankcase and compress said air therein, a 30 transfer chamber, conduits connecting the pump chamber of each cylinder with said transfer chamber, and conduits connecting said transfer chamber with the gas admission ports of the explosion chambers, and a 35 piston-valve for each cylinder designed to control the passage of gas to and from the pump chamber of its cylinder and also to admit gas into the explosion chamber immediately after the air admission port is 40 covered by the power piston.

2. In an internal combustion engine, a pair of differential cylinders, each cylinder having a pump chamber provided with an inlet and outlet port and an explosion chamber

ber, a crankcase divided into air compression chambers, one for each cylinder, each of said air compression chambers communicating with the explosion chamber of its cylinder, pistons in said cylinders working in opposite directions, a transfer chamber, a 60 valve cylinder for each differential cylinder, separate passageways leading from a source of fuel supply to said valve cylinders, from said valve cylinders to the pump chamber and also to the explosion chamber of their 65 respective differential cylinders and from said valve cylinders to the transfer chamber, piston-valves for said valve cylinders, said piston-valves each having a plurality of ports and channels therein adapted to register with the passageways communicating with its valve cylinder to admit gas into the pump chamber of one cylinder, then direct said gas therefrom into the transfer chamber and finally to admit gas from said transfer chamber into the explosion chamber. 70

3. In an internal combustion engine, a pair of differential cylinders, each cylinder having a pump chamber provided with an inlet and outlet port and an explosion chamber provided with an exhaust port, a crankcase divided into air compression chambers, one for each cylinder, said chambers communicating respectively with the explosion chambers of said cylinders, pistons in said 80 cylinders working in opposite directions, a transfer chamber, a valve cylinder for each differential cylinder having a passageway communicating with a source of fuel supply, conduits leading from said valve cylinder 85 to the pump chamber, and also to the explosion chamber of its said differential cylinder, and from said valve cylinder to the transfer chamber, piston-valves for said valve cylinders, each of said piston-valves 90 having a plurality of ports and channels therein adapted to register with the passageways communicating with its valve cylinder, whereby gas is admitted into the pump chamber of one cylinder, then directed by 95 its piston-valve to the transfer chamber and admitted by the other piston-valve to the explosion chamber of the companion cylinder. 100

Whereof, I have hereunto subscribed my name to this specification.

JOHN FROELICH.
